UNITED STATES PATENT OFFICE.

ELMER R. CORWIN, OF CLYDE, ILLINOIS, ASSIGNOR TO MONARCH TELEPHONE MANUFACTURING COMPANY, OF CHICAGO, ILLINOIS, A CORPORATION OF ILLINOIS.

TELEPHONE SYSTEM.

No. 888,870.

Specification of Letters Patent.

Patented May 26, 1908.

Application filed May 11, 1906. Serial No. 316,358.

To all whom it may concern:

Be it known that I, ELMER R. CORWIN, citizen of the United States, residing at Clyde, in the county of Cook and State of Illinois, have invented a certain new and useful Improvement in Telephone Systems, of which the following is a full, clear, concise, and exact description, reference being had to the accompanying drawings, forming 10 a part of this specification.

My invention relates to telephone exchange practice, and has a number of objects in view.

It is one of the objects of my invention to 15 eliminate supervisory relays in cord or link circuits, which I accomplish by providing means extraneous to those circuits that co-operate with the plugs of the cord circuits and the jacks in which the plugs are to be 20 inserted to effect the desired control of the supervisory signals, talking strands of the link circuits being employed for this purpose, as are also preferably talking portions of the 25 circuits extraneous to the link circuits.

Where my invention is employed in the 30 circuits used in inter-connecting subscribers, the extraneous means taking part in the control of the supervisory signals (which may be one or more to a link or cord circuit, as 35 desired) desirably resides in the line relays that are also used for effecting calling signals at the exchange. Where cut-off relays are 40 employed to efface the line signals, these cut-off relays, in accordance with another feature 45 of my invention, are adapted for inclusion in the same circuits with the supervisory signals. The cut-off relay and supervisory signal 50 circuits are local, and in order that the government of the line relays and the government 55 of the cut-off relays may be totally distinct, I provide one battery for the cut-off relay and supervisory circuits and another battery for the line circuits, which latter battery may also serve to supply battery current 60 to the transmitters at the sub-stations.

As is well known, the common batteries 50 employed in common battery systems have one pole grounded for circuit protection, and, as my invention is of particular service in connection with multiple switchboard practice, I prevent the occurrence of false signals and improper busy tests by providing one battery for talking purposes and another battery for the supervisory signaling and cut-off

relay devices. The line relays are desirably 55 included in bridge of the telephone lines and in series with the common battery, and in order that the functions of the line relays, on the one hand, and the cut-off relays and the supervisory signals, on the other hand, may 60 perform without interference, I include condensers in the talking circuits between each cut-off relay and the associate line relay, which condensers are desirably permanently included in the lines, whereby a two sided 65 system may be produced that will permit of conversation and also permit of the use of a portion of the talking circuit to enable the functioning of the signaling and cut-off 70 relays, whereby the provision of third conductors for the cord circuits and third parts for the jacks may be dispensed with, though I do not wish to be limited in all embodiments of my invention to these characteristics.

I will explain my invention more fully by reference to the accompanying drawing, and will point out other advantages thereof in connection with the drawing, in which—

Figure 1 illustrates the invention as applied to telephone exchange systems including subscribers' lines. Fig. 2 is a schematic view more briefly outlining the circuits that are shown in Fig. 1.

Like parts are indicated by similar characters of reference in both figures.

There are indicated two of many substations, A, B, each in the embodiment of the invention shown having a transmitter 1, a receiver 2, a call bell 3, a switch-hook 4, a 90 condenser 5, and an impedance coil 6, together with suitable contacts and circuit connections, whereby when the telephone receivers 2 are upon the switch-hooks, the bells 3, together with the condensers 5, are 95 bridged across the sides of the telephone lines 7, 8, and whereby when the telephone receivers are removed from their hooks, the bridges including said signaling bells are 100 opened, the transmitters are thrown into conductive connection with the lines, whereby battery may be fed thereto through the impedance coils 6, and whereby voice currents may be impressed upon the lines at the 105 substations at the transmitters or may be received at the receivers.

I do not wish to be limited to the precise substation circuits indicated. The limbs 7

and 8 of the telephone lines are, in multiple switch-board practice, multiplied to sleeve contact springs 9 and tip contact springs 10, respectively, of multiple spring jacks, though the invention may be useful in connection with switchboards that are not multiple switchboards, in which case but one spring jack need be supplied to a line. In multiple switch-board practice, one of the jacks may 5 act as an answering jack, the answering jacks, as is understood, being suitably distributed among the different sections of the switch-board, the multiple jacks being multiplied to the several sections of the switch-board, which grouping arrangement, or any 10 other preferred grouping, is well understood.

In the embodiment of the invention shown, the line relays 11 have their windings desirably permanently associated with the corresponding telephone lines and the common talking battery 12, the circuit of this talking battery being desirably normally closed at each cut-off relay switch 13, so that when a subscriber removes his telephone, the line relay 11 may become energized, whereby circuit through the line signal 14 of the calling subscriber may become closed by way of a companion cut-off relay switch 15 and the line relay contacts 16, 17, the circuit of the line signal 14 desirably, though not necessarily, including the battery 18 distinct from the battery 12. It is not as important to provide a special battery 18 for the line signals as it is to provide said battery for the 20 supervisory signals and cut-off relays, as will appear.

In the embodiment of the invention shown, there may be a number of cord or link circuits, one being illustrated, each including 25 an answering plug 19 and a connecting plug 20, the tips of the plugs being united by a tip strand 21 while the sleeves of the plugs are united by a sleeve strand 22, condensers 23, 24 being included in the strands of the cord circuits where double supervision is desired. When the battery 12 is employed for the purpose of supplying the transmitters at the substations with current, which employment does not need to begin until the 30 cord circuit is connected with a calling line, I desirably connect one pole, the grounded pole as shown, with a subscriber's line or lines by way of the conductor 25 that has connection between the impedance coils 26, between which the condenser 23 is interposed, the battery 12, assuming now a complete connection between subscribers, supplying current to the substation A from its grounded pole through impedance 26, the 35 tip of the inserted answering plug 19, the tip spring of the jack belonging to subscriber A, the limb 8 of said subscriber's line, through the transmitter 1, the impedance coil 6, the winding of line relay 11, back to the ungrounded pole of the battery 12. A similar

circuit is established through similar parts of the connecting plug for supplying current to the substation B and the line relay 11 corresponding to said substation. When the plugs are inserted into the jacks of connected subscribers, local circuits are established for the cut-off relays 27, each circuit including a common signaling battery 18, a common impedance device 28, the sleeve contacts of the engaging plugs and jacks, the winding of the cut-off relay 27, the contacts 16 and 29 of the corresponding line relay 11, the resistance 30, back to the remaining pole of the battery 18. While the grounded terminal of the battery 12 is now connected with one side of each line by way of the tip strand of the link circuit and is disconnected from the lines at 13, yet the said battery remains effective for further signaling purposes by reason of its continued connection through the line relays 11, which line relays are energized as long as the subscribers have their telephone receivers off their hooks.

It is understood that when a subscriber initiates a call the conditions are such that circuit is closed through the corresponding line signal 14 by reason of the engagement of the parts 16, 17 of the line relay, and that when the operator inserts the answering plug, the cut-off relay 27 of the corresponding calling line is energized to open the circuit of the operated lamp 14 at 15, the cut-off relays thereby desirably effacing the signals by opening the circuits of signaling devices, though I do not wish to be limited to this way of effacing calling signals. It will be seen that the effacement of the calling signals may be effected without interfering with the circuits of the relays that cause these signals, whereby these relays, the line relays 11, may be used to enable the subscribers to effect partial control over the supervisory signals, preferably lamps 31, 32, though I do not wish to be limited to the use of the same relays 11 for enabling the subscribers partially to control the supervisory signals and the line signals. It will be seen that the supervisory signals 31, 32 are included in local circuits containing the cut-off relays, one lamp to a circuit.

During the time the receivers 2 are off their hooks, the line relays 11 are energized and the corresponding supervisory signal is included in circuit with the corresponding cut-off relay 27, the corresponding contacts 16 and 29 and the registering contacts of the corresponding jack and the plug inserted therein, and as the relay 27 is of high resistance, say 600 ohms when a 20 volt battery 18 is employed, the corresponding supervisory or disconnect signal lamp fails to glow until the connection is broken at 16 and 29 and the armature 16 rests against its normal contact upon the deenergization of the corresponding line relay 11 (this operation occurring when the corresponding subscriber restores his tele-

phone upon its switch-hook), whereby the resistance 30, say of 25 ohms, is substituted for the resistance of the cut-off relay 27, permitting the corresponding supervisory signal to glow. The cut-off relays 27 are permanently associated with the subscribers' lines, but, in order that their action may be entirely local, a condenser 33 is associated with each line and affords a path that is continuous to voice currents, but affords conductive separation between the circuits of the corresponding line relay and the corresponding cut-off relay.

It will be seen that each subscriber by restoring his telephone, causes what constitutes a closure of a supervisory lighting circuit at one point, this lighting circuit having previously been closed at another point by the corresponding jack and the inserted plug, this supervisory lighting circuit being broken at this jack of the operator when she withdraws the plug therefrom.

Inasmuch as there are illustrated two supervisory signals 31, 32, and, in order that no extra cord strand need be supplied, I interpose a condenser 24 between the supervisory signals that afford the necessary separation of these signals electrically, while permitting a continuity of the talking circuit.

I have not described the functions and circuits of the operator's listening key 34 and ringing key 35, as the use of these agencies and associate parts is sufficiently well understood by those skilled in the art.

It will be seen that the supervisory signal circuits, in the embodiment of the invention shown, include each a talking contact (as 9) of a jack and the talking contact (as the sleeve contact) of a plug.

The test circuit is clearly illustrated, the busy condition of the line being manifested by a click in the operator's receiver. If an operator with a connecting plug, tests a line that is already busy, the test circuit is established from the upper pole of battery 18, through the impedance device 28, the called subscriber's supervisory signal lamp 32, the sleeve of the plug already inserted into a jack of the busy line at another section of the switch-board, the testing thimble of the jack being tested, the tip of the connecting plug that is performing the test, the operator's receiver 36, the impedance test coil 38, the operator's listening key being actuated, back to the lower pole of the battery 18, this being the circuit that is established when a plug has previously been inserted at another section of the switch into the jack of a calling subscriber. Prior to the insertion of a plug into the jack of a calling subscriber, and owing to the removal of the calling subscriber's telephone from its switch-hook, the lower terminal of battery 18, the calling subscriber's jack thimbles are made busy, for it will be seen that the upper pole of the battery 18 is connected with these test thimbles

by way of the line lamp 14 and the cut-off relay 27, this connection existing, of course, only until the operator responds.

While I have indicated metallic circuit lines, I do not wish to be limited to the same.

I have herein shown a telephone exchange system in which the cord circuits are each provided with two plugs and I have shown spring jacks for receiving the answering plugs. It is obvious, however, that characteristics of my invention are applicable to other types of telephone exchange systems, and I do not, therefore, wish to be limited to those systems in which link circuits having two manually operated plugs are employed. While I have shown spring jacks for the telephone lines, I do not wish to be limited in all embodiments of the invention to such types of connecting switches.

It will be seen that I have provided a telephone exchange system including metallic telephone lines extending to an exchange where double talking conductor cord circuits are employed and where supervisory or disconnect signal circuits are employed that are local to the exchange. These are important features of the system herein shown and forming the subject matter of certain of the claims.

It will be seen that by the system illustrated I am enabled to accomplish all of the results hitherto outlined, and while I prefer the embodiment of the invention specifically set forth and illustrated, I do not wish to be limited to the precise instrumentalities shown, as modifications may be made without departing from the spirit of my invention, but,

Having thus described my invention, I claim as new and desire to secure by Letters-Patent the following:

1. In a multiple switch-board system, the combination with metallic telephone lines each terminating at the exchange in a plurality of jacks or connecting switches, a double talking conductor cord circuit for connection with the jacks, a disconnect signal, a circuit therefor local to the exchange including a portion of a talking conductor of the cord circuit, registering contacts of a jack or switch and the plug or switch of the cord circuit engaging said jack, a line signal-effecting relay in association with the telephone line acting in combination with the said plug and jack to govern the operation of the disconnect signal, apparatus at the stations of the telephone lines governing the operation of the line relays, a cut-off relay for effacing the line signal included in the same circuit with the disconnect signal, said line relay effecting the operation of said line signal when a call is initiated over said telephone line, one battery or source of current for supplying the line relays of said telephone lines and the transmitters at the subscribers' stations of said lines, another battery dis-

tinct from the aforesaid battery adapted to be included in the disconnect signal circuit, a test circuit including said latter battery, a sleeve contact of an inserted plug, the 5 thimble of the jack receiving said plug, the test contact of the connecting plug, the disconnect signal, and a testing device in circuit with said test contact.

2. In a multiple switch-board system, the
10 combination with metallic telephone lines
each terminating at the exchange in a plurality
of jacks or connecting switches, a
double talking conductor cord circuit for
connection with the jacks, a disconnect signal,
15 a circuit therefor local to the exchange
including a portion of a talking conductor
of the cord circuit, registering contacts of a
jack or switch and the plug or switch of the
cord circuit engaging said jack, a line signal,
20 effecting relay in association with the telephone line acting in combination with the
said plug and jack to govern the operation of
the disconnect signal, apparatus at the stations
of the telephone lines governing the
25 operation of the line relays, the circuit of the
disconnect signal also including a portion of
a talking conductor of the telephone lines, a
cut-off relay for effacing the line signal included
in the same circuit with the disconnect
30 signal, said line relay effecting the operation
of said line signal when a call is initiated
over said telephone line, one battery or
source of current for supplying the line relays
of said telephone lines and the transmitters
35 at the subscribers' stations of said lines, another battery distinct from the
aforesaid battery adapted to be included in
the disconnect signal circuit, a test circuit
including said latter battery, a sleeve contact
40 of an inserted plug, the thimble of the
jack receiving said plug, the test contact of
the connecting plug, the disconnect signal,
and a testing device in circuit with said test
contact.

45 3. In a multiple switch-board system, the combination with metallic telephone lines each terminating at the exchange in a plurality of jacks or connecting switches, a double talking conductor cord circuit for
50 connection with the jacks, a disconnect signal, a circuit therefor local to the exchange including a portion of a talking conductor of the cord circuit, registering talking contacts of a jack or switch and the plug or switch of
55 the cord circuit engaging said jack, a line signal-effecting relay in association with the telephone line acting in combination with the said plug and jack to govern the operation of the disconnect signal, apparatus at
60 the stations of the telephone lines governing the operation of the line relays, a cut-off relay for effacing the line signal included in the same circuit with the disconnect signal, said line relay effecting the operation of said
65 line signal when a call is initiated over said

telephone line, one battery or source of current for supplying the line relays of said telephone lines and the transmitters at the subscribers' stations of said lines, another battery distinct from the aforesaid battery 70 adapted to be included in the disconnect signal circuit, a test circuit including said latter battery, a sleeve contact of an inserted plug, the thimble of the jack receiving said plug, the test contact of the connecting plug, 75 the disconnect signal, and a testing device in circuit with said test contact.

4. In a multiple switch-board system, the combination with metallic telephone lines each terminating at the exchange in a plurality of jacks or connecting switches, a double talking conductor cord circuit for connection with the jacks, a disconnect signal, a circuit therefor local to the exchange including a portion of a talking conductor of the cord circuit, registering contacts of a jack or switch and the plug or switch of the cord circuit engaging said jack, a line signal-effecting relay in association with the telephone line acting in combination with the said plug and jack to govern the operation of the disconnect signal, apparatus at the stations of the telephone lines governing the operation of the line relays, a cut-off relay for effacing the line signal included in the same circuit with the disconnect signal, said line relay effecting the operation of said line signal when a call is initiated over said telephone line, one battery or source of current for supplying the line relays of said telephone lines and the transmitters at the subscribers' stations of said lines, another battery distinct from the aforesaid battery adapted to be included in the disconnect signal circuit, a test circuit including said latter battery, a sleeve contact of an inserted plug, the thimble of the jack receiving said plug, the test contact of the connecting plug, and a testing device in said circuit with said test contact.

5. In a multiple switch-board system, the combination with metallic telephone lines each terminating at the exchange in a plurality of jacks or connecting switches, a double talking conductor cord circuit for connection with the jacks, a disconnect signal, a circuit therefor local to the exchange including a portion of a talking conductor of the cord circuit, registering contacts of a jack or switch and the plug or switch of the cord circuit engaging said jack, a line signal-effecting relay in combination with the telephone line acting in association with the said plug and jack to govern the operation of the disconnect signal, apparatus at the stations of the telephone lines governing the operation of the line relays, the circuit of the disconnect signal also including a portion of a talking conductor of the telephone lines, a cut-off relay for effacing the line signal included in the same circuit with the disconnect signal, said 130

line relay effecting the operation of said line signal when a call is initiated over said telephone line, one battery or source of current for supplying the line relays of said telephone lines and the transmitters at the subscribers' stations of said lines, another battery distinct from the aforesaid battery adapted to be included in the disconnect signal circuit, a test circuit including said latter battery, a 10 sleeve contact of an inserted plug, the thimble of the jack receiving said plug, the test contact of the connecting plug, and a testing device in circuit with said test contact.

6. In a multiple switch-board system, the 15 combination with metallic telephone lines each terminating at the exchange in a plurality of jacks or connecting switches, a double talking conductor cord circuit for connection with the jacks, a disconnect signal, a 20 circuit therefor local to the exchange including a portion of a talking conductor of the cord circuit, registering talking contacts of a jack or switch and the plug or switch of the cord circuit engaging said jack, a line signal 25 effecting relay in association with the telephone line acting in combination with the

said plug and jack to govern the operation of the disconnect signal, apparatus at the stations of the telephone lines governing the operation of the line relays, a cut-off relay 30 for effacing the line signal included in the same circuit with the disconnect signal, said line relay effecting the operation of said line signal when a call is initiated over said telephone line, one battery or source of current 35 for supplying the line relays of said telephone lines and the transmitters at the subscribers' stations of said lines, another battery distinct from the aforesaid battery adapted to be included in the disconnect signal circuit, 40 a test circuit including said latter battery, a sleeve contact of an inserted plug, the thimble of the jack receiving said plug, the test contact of the connecting plug, and a testing device in circuit with said test contact. 45

In testimony whereof, I hereunto subscribe my name this 27th day of April A. D. 1906.

ELMER R. CORWIN.
